UNITED STATES PATENT OFFICE

EDWARD H. BELDEN, OF TOLEDO, OHIO, ASSIGNOR TO BELDEN PATENTS INCORPORATED, OF TOLEDO, OHIO, A CORPORATION OF OHIO

TWO-CYCLE V MOTOR

Application filed December 21, 1923. Serial No. 682,001.

My invention relates to an internal combustion motor, and more particularly to such a motor of the two-cycle V type.

My invention has for its object to produce a compact, powerful and efficient motor that will produce the minimum of vibration and noise. The manner in which I achieve the objects of my invention can be best described in connection with the embodiment thereof illustrated in the accompanying drawing, in which,

Fig. 1 is a transverse vertical section of such a motor, and Fig. 2 is a diagrammatic showing of a slightly modified form.

Two working cylinders 10, 11 are arranged preferably with their axes inclined so that they will form the two sides of a V. It will be noted that the V-arrangement of the cylinders allows the crank shaft to be located centrally, and the lines of stress are substantially to and from this central line, each of which features tends to lessen vibration when the motor is mounted in an automobile or other vehicle. Furthermore, the arrangement shown is much more compact than would be an arrangement with the cylinders parallel. Two charging cylinders, 12 and 13, are arranged outside of and parallel with the working cylinders. The pistons 14, 15, 16 and 17 of the respective cylinders have rods 18, 19, 20 and 21 pivoted to a lever or beam 22. The beam 22 is fulcrumed at a point 23 between and slightly below the working cylinders. Directly beneath the fulcrum point 23 there is a crank shaft 24. The crank pin 25 of a crank on the shaft is connected by a link 26 to a pivot 27 on one arm of the beam 22. I prefer to locate the pivot 27 between the pivots 28 and 29 of the piston rods 18 and 20, respectively.

The working cylinders 10 and 11 have exhaust ports 30 and 31 in their sides just above the lowest points reached by the tops of their respective pistons, and these ports are shown leading into exhaust pipes 32 and 33. The charging cylinders 12 and 13 have inlet ports 34 and 35 leading through connections 36 and 37 from any suitable source of fuel supply. A common head over the cylinders 10 and 12 has a cavity 38 opening di-

rectly into the cylinder 10, while a similar head over the cylinders 11 and 13 has a like cavity 39 opening directly into the cylinder 11. The cavities 38 and 39 are connected to the charging chambers through ports controlled by check valves 40, 41, which are preferably pressed to their seats by springs 42 and 43. Firing means, such as spark plugs 44 and 45, are provided, preferably adjacent the points where the cavities 38 and 39 open into cylinders 10 and 11, respectively.

I prefer to construct my engine of the compound type, and show accordingly on the crank shaft a second crank pin 46, which is connected by a link 47 to the beam 48, which is similar in all respects to the beam 22 and is connected in a similar way to a similar series of pistons. The position of the beam 48 in the form shown in Fig. 1 is the same as that shown diagrammatically for this beam in Fig. 2, and the working piston connected to its right end and indicated at 50 in Fig. 2 is at the bottom of its stroke while the piston connected to the left end of the beam and indicated at 51 is at the top of its stroke, and the corresponding charging pistons 52 and 53 will of course move simultaneously with the working pistons.

The operation of the motor will be apparent from the description of its structure, but for convenience will be briefly stated as follows:

Presuming the crank to be rotating in a clockwise direction, as shown on Fig. 1, the pistons 15 and 17 are moving upward and, after they pass and close the respective ports 31 and 35, the charge from the cylinder 13 is driven through check valve 41 into chamber 39 and cylinder 11. When the pistons reach the tops of the cylinders the charge is exploded, check valve 41 closing and the piston 15 being driven down on its working stroke. In the meantime, while the pistons 15 and 17 are rising, piston 14 is moving down on its working stroke and piston 16 creates a partial vacuum in the cylinder 12. When the piston 14 uncovers port 30 the burned gases in cylinder 10 are exhausted, and when piston 16 uncovers ports 34 the fuel gases rush into the cylinder 12 to fill the vacuum. While

piston 15 is moving down on its working stroke piston 16 is moving upward and charging fuel gases into the cavity 38. As will be noted, the piston 16 is moved very close to the top of the cavity in the cylinder 12, so that nearly all of the charge is forced out of the cylinder 12. Under some circumstances it might be desirable to leave a larger space at the upper end of the charging cylinder, to form a chamber in which gases might be compressed without unseating the check valve after firing by a considerably advanced spark. However, owing to the thorough mixture of the gases and the location of the spark plug directly over the working piston, the best results are provided with less advancement of the spark than has been customary with other motors. Clearance at the top of the charging cylinder has several disadvantages. For one thing, it requires a considerably larger charging cylinder to force the same amount of fuel into the combustion chamber. Furthermore, a very desirable feature of the structure shown is the comparatively high degree of vacuum in cylinder 12 when the intake port is uncovered. This results in a comparatively rapid flow of gas into the cylinder and when the parts are properly proportioned this flow is so rapid that the gas has a turbulent rather than a stream line flow, and the resulting mixture of gases is much more thorough than where the flow is slower. This thorough mixture of gases is obviously a very desirable feature, as it increases both the rapidity and the completeness of the combustion of the gases.

In the structure shown the charging piston moves some distance below the charging inlet, as indicated by the position in which piston 17 is shown. This is for the purpose of allowing time for the gases to completely fill the charging cylinder, and the distance which the charging piston moves below the inlet port will, of course, depend upon the size of the cylinder, the amount of charge desired, the size of the inlet ports, the feeding means by which fuel gases are supplied to these ports, and the degree of vacuum in the chamber at the time the ports are uncovered. I prefer to introduce a larger charge than can be drawn in by the working piston in the usual four-cycle operation. Amongst other results of this increased charge are greater cooling of unexhausted gases and increased power.

With the parts arranged as in Fig. 1, the working strokes of the pistons 14 and 51 will be simultaneous, and at the same time that link 26 is pushing in one direction upon the crank shaft 24, as a result of the working stroke of piston 14, the link 47 will be pulling in the opposite direction as the result of the working stroke of piston 51, and the same result will occur with the subsequent simul-

taneous working strokes of pistons 50 and 15. Such side thrust as develops from the differing angles at which the forces of the two links are applied during the revolution of the crank in a clockwise direction has a tendency to move the shaft towards the point at which the indicating numeral 24 is applied on Fig. 1, and so will not raise the shaft even though its bearings are worn.

In the modification shown in Fig. 2 the connection of the front beam or beam 22' is changed by attaching the link 26' to a pivot point 27' on the left of the beam, instead of on the right of the beam. In this case when the piston 51 is starting its working stroke the piston 11' will be half way through its working stroke, and when the pivot point 46 has moved to the point indicated at 54 and the crank pin 25 has moved to the point indicated at 55, cylinder 10' will begin its working stroke and the piston 51 will be halfway through its working stroke. As will be seen without further description, the four working strokes will continue to succeed each other at each quarter revolution of the crank shaft. This gives a somewhat more continuous torque to the crank shaft, but does not have the advantage of balancing the forces applied to the two cranks as well as the method of attachment shown in Fig. 1. As will be seen in Fig. 1, the two arms of the beams are bent downward so that they are at an angle to each other, and I prefer to have this angle substantially the supplement of the angle between the axes of the cylinders. By this arrangement and by the proper proportioning of the cranks and the length and pivot point of the link connecting the crank to the beam, a very compact arrangement can be constructed with the crank shaft at or slightly above the point of the V formed by the axes of the working cylinders, so that the enclosing crank case 56 need not be larger than with the usual type of direct connection between the pistons and crank shaft.

It is an advantage to have the link from the crank pin pivoted to the beam between the working piston and the charging piston. By having this pivot point outside of the pivotal connection to the working piston the pressure always remains in a downward direction on the fulcrum 23. It will also be noted that in this type of engine the connections between the working piston and the beam will always be under pressure, so that there will be no change from push to pull on the pivot points and consequently there will be no occasion for vibration or knock if these points are slightly loose. In like manner the pressure is either balanced or downward on the crank shaft in the structure shown in Fig. 1, so that there is no abrupt change in the direction of the forces applied

to the crank shaft which might result in knock in that shaft. Furthermore, as shown at the right of Fig. 1 by the dotted lines 60 and 61, pivot points 28 and 29 will travel closely to the respective axes of cylinders 10 and 12, indicated by dotted lines 62 and 63, but will always remain slightly on the inner side of those lines, with the result that the pressure between the pivot points 28 and 29 and their respective pistons always tends to force the pistons towards the outer or lower sides of the cylinders, towards which they are urged by gravity, and the result is that there is no tendency to move the pistons from one side to the other side of the cylinder with the result of what is sometimes called piston slap.

If the arrangement is such that the pivot points to which the piston rods are attached remain constantly outside of the axial lines of their respective cylinders, pressure of the rods urges the pistons against the upper sides of their cylinders, and eliminates slap due to varying directions of piston rod pressure. This is preferable to having the pivot points cross the axial lines, but may allow slight slap where gravity and pressure on the rods are alternately greater. When the cylinders are arranged vertically, the side of the axial line upon which the pivot points remain does not make any difference so far as piston slap is concerned.

The pivot point 27 is below a line passing through pivots 23 and 28, and as a result the distance between the pivot 27 and the vertical line passing through the fulcrum decreases with its descent at a relatively greater speed than the distance between the pivot 28 and the same line.

As a result of these various features, it will be seen that I have constructed a motor that is very compact and at the same time powerful, as each working cylinder has a two-cycle action, that is efficient, due to the thorough mixture of the gases and for other obvious reasons, and that will cause but little vibration or noise, due to the balanced features and the comparative absence of change in direction of stresses in the moving parts.

Various modifications could be made in the structure, such as the substitution of different types of valves, the use of valved inlets at the top of the charging cylinders instead of near the bottom, and similar changes, within the scope of the appended claims, while still retaining the advantages of some of the features of the invention.

I claim:

1. In an internal combustion motor, a working cylinder and piston, a charging cylinder and piston at one side of and substantially parallel with the working cylinder, there being a port connecting adjacent ends of the two cylinders, and an inlet port uncovered by the movement of the charging pis-

ton near the end of its travel away from the connecting port, and connections to move the charging piston simultaneously with and always in the same direction as the working piston.

2. In an internal combustion motor, a working cylinder and piston, a charging cylinder and piston at one side of and substantially parallel with the working cylinder, there being a port connecting adjacent ends of the two cylinders and an inlet port uncovered by the movement of the charging piston near the end of its travel away from the connecting port, and connections to move the charging piston simultaneously with and always in the same direction as the working piston.

3. In an internal combustion motor, a working cylinder and piston, a charging cylinder and piston at one side of and substantially parallel with the working cylinder, there being a port connecting adjacent ends of the two cylinders, and a check valve for the port opening towards the working cylinder, there being an exhaust port in position to be uncovered by the movement of the working piston near the end of its travel away from the connecting port and an inlet port in position to be uncovered by the movement of the charging piston near the end of its travel away from the connecting port.

4. In an internal combustion motor, a working cylinder and piston, a charging cylinder and piston at one side of and substantially parallel with the working cylinder, a lever having an arm at one end of the cylinders, and rods connecting the pistons to the lever arm.

5. In an internal combustion motor, a working cylinder and piston, a charging cylinder and piston at one side of and substantially parallel with the working cylinder, there being a port connecting adjacent ends of the two cylinders, a lever fulcrumed at the opposite side of the working cylinder from the charging cylinder, and piston rods connecting the pistons to the lever.

6. In an internal combustion motor, a working cylinder and piston, a charging cylinder and piston at one side of and substantially parallel with the working cylinder, there being a port connecting adjacent ends of the two cylinders, a lever fulcrumed to one side of the cylinders, and piston rods connecting the piston to the lever.

7. In an internal combustion motor, a working cylinder and piston, a charging cylinder and piston at one side of and substantially parallel with the working cylinder, there being a port connecting adjacent ends of the two cylinders, a lever fulcrumed to one side of the cylinders, piston rods connecting the piston to the lever, a crank, and a link connecting the crank to the lever.

8. In an internal combustion motor, a

working cylinder and piston, a charging cylinder and piston at one side of and substantially parallel with the working cylinder, there being a port connecting adjacent ends of the two cylinders, a lever fulcrumed at the opposite side of the working cylinder from the charging cylinder, piston rods connecting the piston to the lever, a crank, and a link pivoted to the crank and to a point on the lever between the points at which the piston rods are connected to the lever.

9. In an internal combustion motor, two working cylinders and two charging cylinders with their axes in the same plane, a charging cylinder being approximately parallel with each working cylinder and on the side thereof farthest distant from the other working cylinder, a beam fulcrumed near its center, and connections between each end of the beam and the piston of one of the working cylinders and the piston of one of the charging cylinders.

10. In an internal combustion motor, two working cylinders with their axes in the same plane, a charging cylinder approximately parallel with each working cylinder and on the side thereof farthest distant from the other working cylinder, a piston in each cylinder, a beam fulcrumed between the extended axes to swing in the plane of the axes, and connections between the pistons and the beam.

11. In an internal combustion motor, two working cylinders with their axes in the same plane, a charging cylinder approximately parallel with each working cylinder and on the side thereof farthest distant from the other working cylinder, a piston in each cylinder, a beam fulcrumed between the axes of the working cylinders to swing in the plane of the axes, connections between the pistons and beam, a crank shaft and a link connecting the crank shaft to a point on the beam between the connecting points of a working piston and a charging piston.

12. In an internal combustion motor, a working cylinder and piston, a charging cylinder and piston at one side of and substantially parallel with the working cylinder, there being a port connecting adjacent ends of the two cylinders, a two-armed lever, piston rods connecting the pistons to one arm of the lever, and a similar pair of cylinders and piston rods connected to the other arm of the lever.

13. In an internal combustion motor, a working cylinder and piston, a charging cylinder and piston at one side of and substantially parallel with the working cylinder, there being a port connecting adjacent ends of the two cylinders, a two armed lever fulcrumed at the opposite side of the working cylinder from the charging cylinder, piston rods connecting the pistons to one arm of the lever, a similar pair of cylinders and piston

rods connected to the other arm of the lever, a crank shaft, and a link connecting a crank on the shaft to the lever between the connection of one of the working pistons and one of the charging pistons to the lever.

14. In an internal combustion motor, two sets of cylinders, each comprising four parallel cylinders arranged substantially in the form of a square, the two sets of cylinders being arranged side by side, the two inner cylinders of each set being working cylinders and the two outer cylinders being charging cylinders, two beams fulcrumed between the two sets of cylinders, each being extended under and connected to the pistons within the four cylinders having their axes in the same plane, a crank shaft having cranks off-set opposite to each other, and a link from each crank to a beam, both links being connected to the beams on the same side of the fulcrum.

15. In an internal combustion motor, two working cylinders with their axial lines forming a V, a charging cylinder at the side of each working cylinder farthest distant from the other working cylinder, a two armed lever fulcrumed midway between said lines, pistons in the cylinders, and rods connecting the pistons to the lever, each rod being connected to a point on the lever nearer its fulcrum than is the axial line of the respective cylinder.

16. In an internal combustion motor, two working cylinders with their axial lines forming a V, a charging cylinder parallel with each working cylinder and on the side thereof farthest distant from the other working cylinder, there being ports connecting the closed ends of each working cylinder with the adjacent end of its associated charging cylinder, a two armed lever fulcrumed midway between said lines, pistons in the cylinders, and rods connecting the pistons to the lever.

17. In an internal combustion motor, two working cylinders with their axial lines forming a V, a charging cylinder parallel with each working cylinder and on the side thereof farthest distant from the other working cylinder, a two armed lever fulcrumed midway between said lines, the two arms being at an angle to each other which is substantially the supplement of the angle between said lines, pistons in the cylinders, rods connecting the pistons to the lever, a crank shaft equi-distant from said lines, and a link connecting a crank on the shaft to a point on one arm of the lever between the points at which a working-piston rod and a charging-piston rod are attached.

18. An internal combustion engine of the V type having on each side four parallel cylinders arranged substantially in the form of a square, the two sets of cylinders being arranged side by side, the two inner cylinders of each set being working cylinders, and the

two outer cylinders being charging cylinders, two beams fulcrumed substantially at the center of the V, each beam extending beneath four cylinders having their axes in the same vertical plane, a piston within each cylinder connected by a rod to the associated beam, a crank shaft vertically beneath the fulcrum and having two cranks off-set opposite to each other, and a link from each crank to a beam, the connections of the links to the beam being on the same side of the fulcrum and between the connections of a working piston and a charging piston.

In testimony whereof I have hereunto signed my name to this specification.

EDWARD H. BELDEN.
